COOKING VESSEL

Original Filed April 28, 1927 2 Sheets-Sheet 2

Inventor:
Henry Schaefer.

By *F. V. Winter*
Attorney

UNITED STATES PATENT OFFICE.

HENRY SCHAEFER, OF BROOKLYN, NEW YORK.

COOKING VESSEL.

Application filed April 28, 1927, Serial No. 187,272. Renewed November 17, 1928.

This invention relates generally to improvements in cooking vessels, for domestic use, having particular reference to the steamer type of cooker.

5 An important object of the invention resides in the provision of an article of the above-mentioned character wherein novel and unique assemblage of parts, all inter-related, results in the instantaneous conveyance 10 of heat units at relatively high temperature to the material to be cooked.

Another object is to provide an assemblage of parts, as set forth in the foregoing paragraph, which will be adaptable to any container, such as a tin pail, or the like, purchasable at any hardware store.

Another object resides in the provision of means in the form of tubes of variable height for permitting the escape of an excess quantity 20 of water, when expanded, to flow out of certain shorter tubes and thereby not interfering with the discharge of steam through certain longer tubes.

Still another object is to provide means for 25 circulating the turbulent boiling water to a point for re-heating in the event an error is made in adding too much water to the cooker.

A still further object of the invention is to 30 provide an article of the above-mentioned character which may be readily and conveniently disassembled for cleaning purposes and which may be constructed at an extremely lesser cost of production, highly efficient in 35 operation and economical in the saving of heat.

With these objects in view, together with others which will appear as the description proceeds, the invention resides in the novel formation, combination, and arrangement of 40 parts, all as will be described more fully hereinafter, illustrated in the drawings, and particularly pointed out in the claims.

In said drawings:

Figure 1 is a central vertical sectional view 45 of the complete cooker.

Fig. 2 is a plan view thereof with the cover portion removed.

Fig. 3 shows a slightly modified form of closure member.

50 Fig. 4 illustrates another slightly modified form of closure member.

Fig. 5 is an inverted plan view of Fig. 4.

Fig. 6 is a modified form of an assemblage of certain cooperative parts.

Fig. 7 is another modified form of the 55 same.

Fig. 8 is a plan view of a warming plate.

Fig. 9 is an elevation thereof; and

Fig. 10 is a central sectional view of a sleeve member.

Referring now more particularly to the accompanying drawings, wherein like characters of reference denote similar parts throughout the several views, the numeral 5 depicts a form of container, having a cover 6 arranged therefor. The particular form or dimensions of said container are of course variable depending on its use so long as a compartment 7 is provided in the upper portion thereof for the reception of vessels containing the vegetables, meat, or other food products to be cooked.

The invention proper comprises the parts positioned within the lower portion of said container 5, shown in Fig. 1. Upon inspection of said Fig. 1 it will be observed that I have provided a perforated member or shield 8, open at the bottom and having an inturned flange 9 at the top thereof defining the opening 10, (see Fig. 2). Arranged concentrically within said shield 8 is a sleeve member 11, having a flared bottom portion, as indicated at 12, the bottom rim thereof being arranged adjacent the inner periphery of the base of said shield 8, while the upper portion 85 of said sleeve or shell member 11 is constricted to present a somewhat elongated extension 13, terminating below said opening 10. Said flared bottom portion of said shell is provided with a row of apertures 11^a, as 90 will be pointed out hereinafter.

The other element of the article, shown in Fig. 1, comprises a closure 14, having a circumferential top rim portion 15 fitting into said opening 10 and having its top surface 95 in the same plane with the top of said in-turned flange 9 of said shield 8. Said closure 14 is further provided with a depending section 16 snugly embracing said extension 13, as clearly shown in the drawing. As shown 100 in Figs. 1 and 2, the top of said closure 14 may be apertured, as indicated at 17, for the reception of a plurality of tubes 18 and 19, the latter being preferably smaller than the

former and terminating below the plane thereof for the purpose clearly announced in the operation of the article hereinafter.

Upon a closer inspection of Fig. 1, it will be noted that the bottom edge of said shield 8 is notched, or serrated, as indicated at 20 and that perforations are both provided in the sides of said shield as well as the inturned flange. These perforations 21, together with the notches 20, establish communication between the exterior and interior, and vice versa, of said shield, and obviously the interior of said sleeve and shell member 11 is in communication with the chamber 7 in view of the openings defined by said tubes 18 and 19.

In the operation of the cooker, a vessel containing the matter to be cooked, is placed above the tops of said tubes 18, as indicated by the dash and dot lines of Fig. 1, depending 20 vertical fillers being adopted to effect the proper spacing if desired. A small quantity of water is placed in said container 5 to the approximate height indicated, which finds its level by circulating through said apertures 21, the serrated bottom of said shield 8 and the apertures 11^a in said shell member 11, when all parts are assembled as clearly shown in Fig. 1. The container is now placed over a gas stove, or the like, and within an appreciably short period of time the water begins 30 to boil and the steam thus generated passes up through the shell 11 and through the opening in the tubes and thus contacts with the bottom of the cooking vessel thereabove. 35 In view of the superabundance of heat, the food material in said vessel is rapidly cooked. In the event too much water has been placed in the container the overflow caused by the expansion of said water will 40 circulate through the shorter tubes 19, which terminate below the other tubes 18, as aforesaid. It should also be remembered that boiling water ejected through said tubes 19 runs out upon the inturned flange 9 of said 45 shield 8 where it may be returned by means of the perforations 21 in said flange; and also when only a small amount of water is present in said container the condensation of the steam generated, if any, may be passed through 50 said perforations 21 back to the water level.

In Fig. 3 of the drawings a modified form of closure member is illustrated. This is substantially similar to the form illustrated in Fig. 1 with the exception that the tubes 18 and 19 may be formed integral with the top portion, as by pressing out operations for instance, in order to reduce the number of joints or seams in said member. Said closure member 14 may be further altered by providing the same with a closed top portion 14^a, as shown in Figs. 4 and 5. This form may be used when it is desired to warm or simmer the contents of a cooking vessel.

Figures 6 and 7 of the drawings are di-

rected toward a modified form or forms of 65 shields 8, each having an inturned top flange 22, bent inwardly for a short distance, as indicated at 23 to define the openings 24, between which is frictionally engaged the extension 13 of said sleeve member 11. In both 70 forms apertured ears 25 may be provided, which are secured to the parts, as indicated at 26, and by the adoption of this means an excellent place is provided for the convenient 75 removal of the parts from the container. At this time it is pointed out that the scope of my invention includes as possibility of adding this removing means to the parts shown in Fig. 1. As distinguished from my other 80 form of shield, the part shown in Fig. 6 is without perforations and in view of the opening in the central portion thereof, I prefer to use a perforated plate 27, (see Figs. 8 and 9), over the top thereof. Obviously an im- 85 perforated plate may be used for warming or simmering purposes. Referring again to the form illustrated in Fig. 7, it will be observed that the striking similarity therebetween ceases with the provision of the openings 28, 90 preferably in the form of notches, for the purpose noted under the description of my preferred form.

In view of the provision of the elongated extension 13 of said member 11, the closure 95 member 14 frictionally engages therewith for maintaining said parts in assembled relation.

All of the parts may be lifted en bloc from the bottom of the container 5, if desired, and then separated for cleansing purposes. 100

While the above presents the preferred forms of the invention, it is to be understood that minor changes and alterations may be made therein without departing from the spirit of the invention or the scope of the appended claims. 105

I claim:

1. In a cooking vessel, a shield having a notched bottom edge and presenting a top 110 inturned flange defining an opening, a shell mounted concentrically within said shield and a perforated closure fitting within said opening and frictionally engaging the upper portion of said shell.

2. In a cooking vessel, a perforated shield having a notched bottom edge and presenting a top inturned flange defining an opening, a shell mounted concentrically within said shield and having a restricted top extension 120 and a perforated closure fitting within said opening and frictionally engaging the extension of said shell. 115

3. In a cooking vessel, a perforated shield having a notched bottom edge and presenting a top inturned flange defining an opening, a 125 shell present an outwardly flared portion concentrically mounted within said shield and having a restricted top extension and a

perforated closure fitting within said opening and frictionally engaging the extension of said shell.

4. In a cooking vessel, a perforated shield having a notched bottom edge and presenting a top inturned flange defining an opening, a shell mounted concentrically within said

shield and having a restricted top extension, a perforated closure having a depending portion frictionally engaging said extension and a plurality of tubes mounted in the top portion of said closure and of varying heights. 10

In testimony whereof I affix my signature.
HENRY SCHAEFER.
